CASH REGISTER

Elmer J. Stoltz, Castro Valley, and William J. Wohltmann, Jr., Mountain View, Calif., assignors to The Singer Company, New York, N.Y.

Filed Dec. 1, 1969, Ser. No. 20,327

Term of patent 14 years

Int. Cl. D20—99

U.S. Cl. D52—4

FIG. 1 is a front and side perspective view of a cash register embodying our new design; and

FIG. 2 is a side and rear perspective view thereof, the undisclosed side being substantially a mirror image of the side shown.

We claim:

The ornamental design for a cash register, as shown and described.
